(57) **CLAIM**

The ornamental design for a wind direction estimation device for golf players as shown and described.

DESCRIPTION

FIG. 1 is a front perspective view of a wind direction estimation device for golf players showing my new design; FIG. 2 is a front elevational view thereof;

FIG. 3 is a rear plan view thereof;

FIG. 4 is a top plan view thereof;

FIG. 5 is a bottom plan view thereof;

FIG. 6 is a left elevational view thereof;

FIG. 7 is a right elevational view thereof; and,

FIG. 8 is the wind direction estimation device for golf players placed on golf cart thereof.

The broken lines shown in the drawings represent portions of the golf cart shown in FIG. 8 that forms no part of the claimed design.
